UNITED STATES PATENT OFFICE.

HENRY W. BULKLEY, OF EAST ORANGE, NEW JERSEY.

STEAM-ACTUATED VALVE.

SPECIFICATION forming part of Letters Patent No. 377,423, dated February 7, 1888.

Application filed November 13, 1885. Serial No. 182,688. (No model.)

To all whom it may concern:

Be it known that I, HENRY W. BULKLEY, a citizen of the United States, residing at East Orange, in the county of Essex and State of New Jersey, have invented a new and useful Improvement in Steam-Actuated Valves for Direct-Acting Engines, of which the following is a specification, reference being had to the accompanying drawings, forming a part of the same, in which—

Figure 1 represents a vertical section through the steam-cylinder and valve-chest; Fig. 2, a plan view of the same with the cover removed; Fig. 3, also a plan view with the main slide-valve removed to show the main and auxiliary steam and exhaust ports; Fig. 4, a vertical transverse section of the steam-cylinder, valve-chest, and auxiliary cylinder; and Fig. 5, a plan view of the auxiliary cylinder and main slide-valve to show the position of the steam and exhaust ports of the auxiliary cylinder.

Similar letters of reference indicate corresponding parts in the several figures.

The object of my invention is to simplify and cheapen the construction of an automatic valve-motion for direct-acting engines, pumps, air-compressors, and the like, and to render the parts of the valve mechanism more accessible within the valve-chest, and readily removable therefrom to facilitate the construction and repair of the same.

In the drawings, A is the main cylinder, and X Y Z steam and exhaust ports covered by the main cylinder-valve B, which operates upon a seat, I, within the steam-chest J. A seat, I', is formed in the chest adjacent to the seat I, and upon which is fitted the auxiliary cylinder D, which has steam and exhaust apertures formed in its bottom flange, D', to fit corresponding apertures in the seat I', and is provided with a tappet-rod, F, by which it is shifted at each stroke of the main piston.

G is the main piston, G' its rod, and H a tappet-lever oscillated thereby and operating, through a stud, K², upon tappets L L' upon the rod F. The rod F is provided at its inner end with a collar or head, K, and the cylinder D with hooked lugs K', fitted thereto and formed transverse to the seat I', so that the cylinder may be disengaged from the collar

by lifting it from its seat when the cover J' of the chest J is removed, as shown in Fig. 2.

An auxiliary piston, C, is fitted within the cylinder D, and has a rod, E, projected through the head D², (at the inner end of the cylinder D,) and is connected with the valve B by the rotary nut B', fitted between lugs upon the back of the valve B in the usual manner.

The fitting of the valve B and cylinder D to their respective rods E and F permits them to seat themselves steam-tight independently upon their seats I and I'.

The main steam-piston G and slide-valve B are both shown at the end of their rear stroke ready to move forward, the steam-port X having been opened by the combined action of the lever H, auxiliary cylinder D, and piston C. The steam admitted through the port X would then operate to move the piston G and lever H forward until the stud K' engaged the tappet L upon the rod F, when the movement of the cylinder D forward would press the cylinder-head D² against the rear side of the piston C and drag it forward with the main valve until the piston C were independently actuated by the admission of steam to the cylinder D. Such admission is effected by a steam-port, a, extending from a point between the piston and the head D², through the flange D', and connecting with a live-steam port, a', in the seat I'. When such ports are connected, an exhaust-port, b, extending from the opposite side of the piston, also connects with a port, b', in the seat I', so that the steam from the chest J may move the piston forward within the cylinder D and complete the stroke of the valve B in the desired manner.

As is well known in such construction, the effect of the tappets upon the cylinder D would be wholly arrested (by the stoppage of the main piston G) when the movement of the valve B closes the port X, the remainder of the valve-stroke being thereafter dependent upon the operation of the steam in the cylinder D, as with other steam-moved valves. When the movement of the valve is thus completed, it would be in a position exactly the reverse to that shown in Fig. 1, with the port X closed and the port Y open to the chest J, so that the steam would press upon the front side of the piston G and force it back to the position

shown in Fig. 1. Before it completely attained such position the stud K', shown in contact with the tappet L', would operate to move the cylinder D to the position shown in Fig. 1. In 5 this position steam and exhaust ports *d* and *e* (communicating with the opposite sides of the piston C) would coincide with exhaust and steam ports *d'* and *e'* in the seat I', to permit the steam to shift the piston C to the position shown 10 in Fig. 1, and thus move the valve B to the position shown in the same figure. A repetition of these movements will occur at each end of the stroke as the piston approaches the end of its travel, the auxiliary cylinder being 15 moved by the tappets sufficiently to admit the steam through the port *a* or *e*, and the remaining movement of the valve required to reverse the motion of the main piston being completed by the movement of the piston C within the 20 auxiliary cylinder.

The exhaust-ports *d* and *e* are preferably arranged, as shown in Fig. 5, closer together than the steam-ports *a* and *b*, the piston C being thus compelled to pass over the exhausting 25 ports before it has wholly moved the valve B, and thus compressing the waste steam remaining in the cylinder D and cushioning the piston C at the ends of its stroke.

Should the auxiliary piston fail from any 30 cause to move promptly, the stoppage or reversal of the main piston G would be safely and positively effected by the continued movement of the stud in contact with the tappets, operating to drag the piston C with the cylinder D, until the valve B had wholly cut off the steam supplied to one side of the main piston, or admitted it to the opposite side to reverse its movement.

My device consists of very few parts, which 40 are easily and cheaply constructed, and require no exact fitting together to match their respective valve-seats, as the sliding joint of the head K with the cylinder D and of the nut B' with the valve B permits each to seat 45 itself accurately, regardless of the exact distance of such seats from the centers of the rods E or F. The form of such sliding joints also permits the cylinder D to be removed from the chest and the valve B to be detached from 50 the rod F so that the cylinder-head D' may be immediately removed if the piston C or the interior of the cylinder requires examination. The construction of such sliding joints also permits the auxiliary cylinder and slide-valve 55 to be replaced in the chest after examination without danger of derangement, thus avoiding all necessity for the readjustment of any of the parts.

The size and particular construction of the 60 auxiliary cylinder depends upon the size and style of the main valve to be moved, and may be operated either by a lever or tappet, as shown, or by other equivalent means, as most desirable. The steam and exhaust ports of the 65 auxiliary cylinder and its valve-seat may also

be differently located, so as to vary the time for opening and closing the passage to the former, as may best be determined in practice.

The valve-seats I and I' are shown projected a little above the bottom of the steam-chest, 70 but not upon the same plane, and the steam is admitted to the ports *a'* and *e'* by cutting them out through the edge of the seat into communication with the steam in the chest; but the ports may be supplied with steam by a drilled 75 passage, as shown at B² in Fig. 3, to connect the exhaust-ports in the seat I' with the main exhaust-passage Z.

Beside the advantages mentioned, the construction also avoids the use of any valve 80 moved separately from the cylinder D to distribute the steam to the opposite sides of the piston C in the desired manner and the employment of a separate rod to actuate such auxiliary valve.

I am fully aware that it is not new in a direct-acting steam-engine to move the main steam-valve partly by a tappet-connection and partly by the pressure of steam upon a piston connected with such valve; and I am also aware 90 that an auxiliary cylinder and piston have been used in other combinations, but operating in a manner different from mine, to effect the final movement of a main steam-valve. Such combinations are shown in United States 95 Patent No. 180,433, dated August 1, 1876, and in British Patent No. 629 of 1876, in both of which cylinders and pistons are shown combined with a main cylinder-valve to operate it as a cut-off valve. In both of the said 100 patents it is claimed that the cylinder and piston may, either of them, be attached to the slide-valve, and that the said valve is closed at some period prior to the end of the main piston's stroke by a simultaneous movement in opposite 105 directions of the said valve-moving piston and cylinder, the motion of the slide-valve being a resultant of the two movements of the associated piston and cylinder. In my construction the valve-moving piston and cylinder never actuate the valve by moving in opposite directions, but operate conjointly in the same direction to produce the required stroke of the valve. Neither is there in any of the 110 constructions shown in the said two patents 115 the same arrangement of the same parts which I employ, and which renders my construction wholly independent of any auxiliary valve.

I wholly disclaim the patents cited above and the mere use of a cylinder and piston for moving a slide-valve, as their use was known long prior to the date of the patents cited; and I also disclaim the connection of the slide-valve with a rod projected from a piston through the head of a moving cylinder, as such 125 a construction is shown in the aforesaid patents, but operated by moving the cylinder and piston in opposite directions to give the valve a resultant movement, while my invention differs from such a construction in its functions, 130

in the connection of its parts, and in its mode of operation. I therefore do not claim such constructions, broadly; but,

Having set forth the nature and advantages 5 of my own construction, what I claim herein is—

1. In a direct-acting engine, the combination, with the main slide-valve, of the auxiliary piston C, connected therewith by rod E, 10 the auxiliary cylinder D, connected at one end with the tappet-rod F, and provided at the other end with the head D², perforated for the rod E, and suitable steam and exhaust ports to admit the steam alternately to the opposite 15 sides of the piston C, the cylinder operating, when moved by the tappet-rod, to press the piston and move the slide-valve a part of the required stroke, and the piston C, when supplied with steam, moving in the same direction to complete the stroke of the slide-valve, as and for the purpose set forth.
2. In a direct-acting engine, the combination, with the steam-chest having valve-seats I and I', provided with steam and exhaust 20 ports, of the main slide-valve fitted to the seat 25

I, the auxiliary piston C, connected therewith by rod E, the auxiliary cylinder D, connected at one end by a transversely-sliding joint with the tappet-rod F, and provided at the other end with the head D², perforated for the rod 30 E, the cylinder being fitted to the seat I' and provided with steam and exhaust ports, the cylinder operating, when moved by the tappet-rod, to press the piston and move the slide-valve a part of the required stroke, and the 35 piston C, when supplied with steam, moving in the same direction to complete the stroke of the slide-valve, as and for the purpose set forth.

3. In a direct-acting engine, the combination of the main cylinder and piston, the main valve, and the connected auxiliary cylinder and piston, the respective cylinders being provided with steam and exhaust ports, located 40 and relatively arranged substantially as described. 45
